UNITED STATES PATENT OFFICE

165,824

JUICE DISPENSER

Oswald W. Collins, Jacksonville, Fla.

Application December 22, 1950, Serial No. 13,552

Term of patent 14 years

(Cl. D2—3)

To all whom it may concern:

Be it known that I, Oswald W. Collins, a citizen of the United States, residing at Jacksonville, in the county of Duval and State of Florida, have invented a new, original, and ornamental Design for a Juice Dispenser, of which the following is a specification, reference being had to the accompanying drawing, forming a part thereof, wherein:

I claim:

The ornamental design for a juice dispenser, substantially as shown.

OSWALD W. COLLINS.
